DESIGN FOR A SOUNDING SIGNAL

Joe White, Anderson, Ind., assignor to General Motors Corporation, Detroit, Mich., a corporation of Delaware

Application February 19, 1937, Serial No. 67,751

Term of patent 14 years

To all whom it may concern:

Be it known that I, Joe White, a citizen of the United States, residing at Anderson, in the county of Madison and State of Indiana, have invented a new, original, and ornamental Design for a Sounding Signal, of which the following is a specification, reference being had to the accompanying drawing, forming part thereof.

In the drawing:

Fig. 1 is a side view of the sounding signal showing my new design.

Fig. 2 is a bottom view thereof.

Fig. 3 is a front view thereof.

The sounding signal illustrated comprises a dome portion substantially semi-spherical surmounting a base portion, the underside of which has a spiral configuration ending in a bell whose end plane is substantially normal to a plane situated at the base of the dome.

I claim:

The ornamental design for a sounding signal substantially as shown and described.

JOE WHITE.
